UNITED STATES PATENT OFFICE.

WILHELM GRIESSE, OF DENVER, COLORADO.

ICE-MAKING APPARATUS.

1,018,705.

Specification of Letters Patent. Patented Feb. 27, 1912.

Application filed April 12, 1911. Serial No. 620,615.

To all whom it may concern:

Be it known that I, WILHELM GRIESSE, a citizen of the United States, residing at Denver, in the county of Denver and State 5 of Colorado, have invented new and useful Improvements in Ice-Making Apparatus, of which the following is a specification.

The present invention has reference to improvements in ice making apparatus, and 10 more especially in the formation of the building, room or other structure wherein the freezing operation and the subsequent re-cooling of the refrigerating medium take place.

15 It resides primarily in the provision of a refrigerating structure containing separate tanks or chambers for the carrying out of the two operations specified, the arrangement of parts being such that the brine is 20 caused to circulate through the freezing tank or chamber, and, on leaving that chamber, to enter a second chamber or tank wherein it is cooled and then discharged into a pump or similar operating element 25 which again forces it into the freezing tank. By reason of this arrangement, the employment of cooling coils, or the like, in the freezing tank or chamber is obviated, and, in consequence, the trouble and difficulty or 30 dinarily attendant upon the cleaning and repairing of such coils.

The invention also comprehends certain further improvements, hereinafter specified, in the construction of the tanks or chambers 35 themselves and the therewith directly associated parts or features.

A structural embodiment of the invention is illustrated in the accompanying drawings, wherein—

40 Figure 1 is a plan view, with parts broken away and in section, of the improved freezing and brine-cooling tanks. Figs. 2, 3 and 4 are fragmental vertical sections on enlarged scales taken, respectively, on the 45 lines 2—2, 3—3 and 4—4 of Fig. 1; Fig. 5 is a fragmental perspective view, partly in section, showing the construction of one of the main supporting beams employed in the freezing tank; and Fig. 6 is a perspective 50 view of one of the connecting beams associated with said main beams.

The structure shown in the said drawings is designed primarily for the manufacture of the so-called "can ice", but the circulating system employed may be used with 55 equal facility in manufacturing "plate ice",

and it will be understood, therefore, that such of the appended claims as relate to said system convey no specific limitation to the making of either kind of ice. Said 60 structure is preferably built or constructed, in the main, of concrete, and comprises essentially the two side walls 7 and 8, the outer end wall 9 and the bottom wall or foundation 10, the several walls having their 65 inner surfaces preferably lined or faced with terra-cotta tiles or the like, as indicated by the numeral 11, which are, in turn, faced with a layer 12 of cement or concrete. The bottom wall 10 is also preferably provided 70 with an insulating filling 13 of cinders or the like. Between the two side walls extends a transverse partition wall 14 which forms the inner end wall of the several main chambers or tanks hereinafter described and 75 is constructed in the same manner as the other walls, the said side walls and the bottom wall being extended beyond this wall or partition until they meet the inner end wall (not shown) of the building proper. 80 The space inclosed by the walls 7, 8, 9 and 14 is divided longitudinally by a main partition wall 15, one of the two chambers thus formed (indicated by the numeral 16) constituting the freezing chamber, while the 85 other chamber is divided longitudinally by a wall or partition 17 to produce the brine-cooling and discharging chambers 18 and 19.

The freezing chamber is roofed by a grid-like structure 20 comprising main beams 21 90 and cross- or connecting-beams 22. The beams 21 are, in the construction illustrated, arranged transversely of the chamber, and their ends are supported in seats or pockets 23 formed in the walls 8 and 15; they are 95 preferably constructed in the manner shown in Fig. 5, and consist each of a skeleton frame work of metal, and a filling or body of cementitious material 24. The said frame work itself comprises upper and lower pairs 100 of longitudinally-arranged angle bars 25 and 26 connected together at intervals by straps 27 and cross-bars 28, a series of longitudinally-arranged tie-rods 29, and a similarly-arranged undulatory tie-rod 30, the 105 frame work being placed in a mold which is subsequently filled with the cement or concrete. The upper portion of each beam is slightly reduced in width to produce the continuous longitudinal shoulders 31 upon 110 its opposite side faces, the latter being also formed at intervals with vertical seats 32

and 33; the seats 32 terminate short of the bottom face of the beam to produce the shoulders 34, while the seats 33 have the shape of a bayonet-slot. The cross-beams 5 are in the form of separate blocks whose ends fit in the seats 32 and are supported upon the shoulders 34.

The above described arrangement of the beams comprising the grid 20 is such that a 10 series of rows of spaces or compartments will be produced, the side walls of each compartment being provided with centrally located seats 33. In each compartment is disposed a suitable can 35 whose top has se- 15 cured thereto a bar 36, or the like, the ends of which are engaged and held in place in the horizontal arms or branches of said seats, thereby maintaining the can in properly submerged position. The cans are, how- 20 ever, omitted and replaced by other suitable devices where the manufacture of "plate-ice" is contemplated, as will be understood. The grid is floored over in the usual manner by the removable covers 37 which rest upon 25 the upper faces of the beams 21 and, also, upon the shoulders 31.

The brine or other refrigerating medium is supplied to the freezing chamber 16 from a longitudinal pipe 38 arranged between 30 wall 8 and the first longitudinal row of cans and provided with a series of laterally-directed nozzles 39 corresponding in number to the number of cans in such row. Said pipe extends at its inner end through an 35 opening in wall 14 and is jointed at that point to a pipe 40 leading from a force pump 41 or like motive element arranged within a chamber 42 located at one end of the cooling and discharging chambers 18 and 40 19. This pump may be of any suitable type and may be driven in any preferred manner.

The brine flowing through the nozzles 39 into the freezing chamber, fills the latter and surrounds the cans therein up to a point ap- 45 proximately level with the lower faces of the pockets 33, the wall 15 being formed at about the point indicated with a series of openings 43 through which the brine flows into the cooling chamber 18. Through this 50 chamber extends a cooling device 44 here shown as in the form of a longitudinal drum or cylinder containing a refrigerating me- dium, the brine, which has become heated during its passage through the freezing 55 chamber, being re-cooled on coming into contact with said device, as will be apparent. The wall 17 which separates the cooling and discharging chambers, is formed at its bottom with a series of outlet apertures 45 60 through which the cooled brine flows into the discharging chamber. In said discharging chamber there is provided a vertical par- tition wall of concrete 46 whose top edge lies in the same horizontal plane as the bottom 65 faces of the openings 43, between which wall

and the adjacent wall 7 is formed a down- wardly inclined gutter or trough 47 opening at its lower end through wall 14 into a pipe or spout 48 that leads into pump 41. The two chambers 18 and 19 may be roofed over 70 with a covering of removable sections 49 similar in the main to the covers 37 and provided for much the same purpose, the said covers 49 being supported upon the shouldered upper ends of the walls 15, 17 75 and 7. Said chambers may also be provided with interiorly-located braces 50 designed to strengthen the walls 15, 17 and 46.

The operation is substantially as follows: Brine is forced from pump 41 through pipe 80 40 into the pipe 38, from which latter it flows through the nozzles 39 into chamber 16, filling the same and freezing the water contained in the cans. From said chamber it flows through the outlets 43 into the chamber 85 18, wherein it is cooled by its passage around the drum or other device 44. On leaving chamber 18 through the outlets 45, it fills chamber 19 and overflows into the trough or gutter 47 whence it is returned to said pump 90 and again forced into pipe 38 for re-circulation.

It will be observed, therefore, that a continuous circulation of the brine is provided for, during which time it is re-cooled upon 95 leaving the freezing chamber. Also, the disposition of the cooling device in a chamber separate from that wherein the ice is formed enables such device to be readily inspected and cleaned, thus reducing the time con- sumed in said operations and obviating the difficulties ordinarily connected with the same. The building itself possesses a maximum degree of strength, rigidity and durability, owing to its substantially integral 100 105 formation.

I claim as my invention:

1. In an ice making apparatus, the combination of successively-communicating freezing, cooling and discharging tanks through which a refrigerating medium is adapted to circulate; a force pump; a pipe leading from the pump into the first-named tank for supplying said medium thereto; means arranged within the second-named tank for cooling said medium when the same flows thereinto from said first-named tank; an inclined discharge member arranged within the third-named tank, into which member the cooled medium is adapt- ed to flow from said second-named tank; and a pipe communication between the lower end of said member and said pump for returning said medium from the former to the latter for re-circulation. 110 115 120 125

2. In an ice making apparatus, a concrete structure having substantially-parallel par- titions dividing the same into successively arranged separate freezing, cooling and dis- charging tanks through which a refrigerat- 130

ing medium is adapted to circulate, the partition between the first- and second-named tanks being formed adjacent its top edge with a series of openings, and the partition 5 between the second- and third-named tanks being formed adjacent its bottom edge with a series of openings, said series constituting a means of communication between the respective tanks; in combination with means 10 for supplying said medium to the first-named tank; a cooling device arranged within the second-named tank; and means for discharging said medium from the third-named tank to said supplying means for re-circulation.

3. In an ice making apparatus, a concrete structure having substantially-parallel partitions dividing the same into successively arranged separate freezing, cooling and discharging tanks through which a refrigerating medium is adapted to circulate, the partition between the first- and second-named tanks being formed adjacent its top edge with a series of openings, and the partition 25 between the second- and third-named tanks being formed adjacent its bottom edge with a series of openings, said series constituting a means of communication between the respective tanks; in combination with a force 30 pump for supplying said medium to the first-named tank; a cooling device arranged within the second-named tank; and means for discharging said medium from the third-named tank to said force pump for re-circulation.

4. In an ice making apparatus, a freezing tank; a grid-like roof therefor comprising spaced main and cross-beams intersecting each other at right-angles, to produce series 40 of rows of compartments, each compartment having its opposite side walls provided with alining bayonet slots; and a freezing receptacle located within each compartment

and having its top provided with a bar whose ends are engaged and supported in 45 the adjacent slots.

5. In an ice making apparatus, a freezing tank; a series of spaced parallel beams extending across the top thereof, each pair of beams having their opposite side faces provided with alined alternately-arranged seats and bayonet slots; a series of connecting blocks arranged at right-angles to said beams and having their ends supported in 50 said seats, said blocks and beams coöperating to produce series of rows of compartments; and a freezing receptacle located within each compartment and having its top provided with a bar whose ends are engaged and supported in the adjacent slots.

6. In an ice making apparatus, a freezing tank having its opposite side walls provided at their top edges with alining longitudinal series of pockets; a series of spaced parallel beams extending across the top of said tank 65 and having their ends supported in said pockets and their opposite side faces provided with alternately-arranged block-receiving and bar-receiving seats; a series of blocks connecting said beams and disposed transversely between the same, said blocks 70 having their ends supported in the first-named seats, to coöperate with said beams in producing a series of rows of compartments; and a freezing receptacle located 75 within each compartment and having its top provided with a bar whose ends are supported in the adjacent second-named seats.

In testimony whereof I have hereunto set my hand in presence of two subscribing witnesses.

WILHELM GRIESSE.
